UNITED STATES PATENT OFFICE.

HERMAN CH. SCHELTLE, OF NEW GLARUS, WISCONSIN.

LETTER OR THE LIKE FILE.

1,280,868.

Specification of Letters Patent.

Patented Oct. 8, 1918.

Application filed September 8, 1916. Serial No. 119,149.

To all whom it may concern:

Be it known that I, HERMAN C. SCHELTLE, a citizen of the United States, residing at New Glarus, in the county of Green, State 5 of Wisconsin, have invented certain new and useful Improvements in Letter or the like Files; and I do hereby declare the following to be a full, clear, and exact description of the invention, such as will enable 10 others skilled in the art to which it appertains to make and use the same.

This invention relates to improvements in letter files or binders.

One object of the present invention is to 15 provide a device of this character which is simple in construction, useful and effective in operation, and which can be manufactured and sold at a low figure.

Another object is to provide a device of 20 this character which will contain a large number of letters, bills, receipts, and the like, and which is provided with novel and efficient means for retaining the papers in proper position therein.

25 Other objects and advantages will be apparent from the following description when taken in connection with the accompanying drawing.

In the drawing:

30 Figure 1 is a plan view of my improved file in open position.

Fig. 2 is a plan view of the back of the file, in open position.

Fig. 3 is an end view of the file in closed 35 position.

Fig. 4 is an enlarged longitudinal sectional view taken on the line 4—4 of Fig. 1.

Referring particularly to the accompanying drawing 10 represents the back of the 40 file which is formed of cardboard, or other suitable stiff material, the same being doubled on itself, along the intermediate line 11, to form a hinge, thereby simulating a book.

A strip of suitable metal, such as brass, 45 and represented by the reference character

12, is formed with elongated and longitudinally extending tongues 13, struck up from the body of the strip. These tongues are passed through the inner edge of one of the sections of the back, near the hinge thereof, 50 and bent flatly against the outer face thereof. Thus the strip is secured in position on the back of the file. Additional tongues 14, are similarly formed and struck up from the strip, but instead of being passed through the back, are disposed inwardly thereof in position to be impaled through letters, receipts, bills, or other like papers which it is desired to keep within the file. These latter tongues are adapted to be bent up to 60 receive the letters or papers thereon, then bent down again to hold the papers against being lost.

It will be understood that the file will be made in different sizes, from those used 65 in offices, to the small ones adapted to be carried in the pocket. The back of the file may be made of any cheap material, as will also the strip secured therewithin, so that the device can be cheaply manufactured, and 70 sold at the five and ten cent stores, at a profit.

What is claimed is:

The combination with a backing, of a fastening metal strip having at each end a 75 pair of tongues struck therefrom with a single resultant opening, the tongues passing through the backing and extending from the opening in opposite directions in the form of oppositely opening hooks, the strip 80 having additional tongues struck therefrom between said pairs of tongues and extending from the strip at the opposite side from the backing.

In testimony whereof, I affix my signature, in the presence of two witnesses.

HERMAN CH. SCHELTLE.

Witnesses:

F. J. MARTY,
T. C. HEFTY.
